UNITED STATES PATENT OFFICE.

CHARLES P. HIDDEN, OF BROOKLINE, MASSACHUSETTS, ASSIGNOR TO THE LAMSON COMPANY, OF BOSTON, MASSACHUSETTS, A CORPORATION OF NEW JERSEY.

CARRIER-DESPATCH POWER-CONTROL SYSTEM.

1,248,657.

Specification of Letters Patent.

Patented Dec. 4, 1917.

Application filed May 6, 1914. Serial No. 836,650.

To all whom it may concern:

Be it known that I, CHARLES P. HIDDEN, a citizen of the United States, residing at Brookline, in the county of Norfolk and 5 State of Massachusetts, have invented certain new and useful Improvements in Carrier-Despatch Power-Control Systems, of which the following is a specification.

This invention relates to a power control 10 system for carrier despatch apparatus and is particularly well adapted to pneumatic despatch tube systems.

It is the object of the present invention, to provide a system in which no dependence 15 need be placed on any time-off mechanism, but rather one in which as soon as a carrier is introduced into a line, the expenditure of power commences, while the instant that the carrier emerges from said line or is delivered 20 at a determined station, the expenditure of power ceases automatically, provided that there is no succeeding carrier in the line, traveling in either direction. If there be such succeeding carriers, then the instant 25 that the last carrier emerges or is delivered at the station for which it is destined, the expenditure of power ceases.

To this end I have invented certain novel pieces of apparatus, which are particularly 30 well adapted to accomplish the purpose in question when embodied in a system of this description. I am aware, however that various changes and modifications may be made in my improved system without departing 35 from the spirit of my invention and also that the said pieces of apparatus are adapted to various other uses. I hence desire to be limited only by the scope of the claims appended hereto.

40 In the accompanying drawings which form a part hereof and in which like reference characters designate like parts, I have exemplified my invention as applied to a pneumatic despatch tube system.

45 Referring to the drawings:

Figure 1 is a somewhat diagrammatic representation of a system of the character in question, in which the flow of air through pneumatic transmission tubes is controlled 50 by valves which in turn are controlled by the apparatus hereinafter particularly described.

Fig. 2 is a similar view of a pneumatic despatch system, in which the motor and blower are directly controlled by my said 55 apparatus.

Fig. 3 is a detail view of a contact device which is disposed at despatching points in the above system.

Fig. 4 is a detail section of certain contact devices which may be disposed adjacent 60 to the respective receiving stations in the above systems.

Fig. 5 is a vertical detail section of a preferred circuit making and breaking device which controls respectively the valves and 65 the motor in the above systems; the section being taken on line V—V of Fig. 6.

Fig. 6 is a transverse section taken on line VI—VI of Fig. 5.

Fig. 7 is a section taken on line VII—VII 70 of Fig. 6.

Fig. 8 is a detail elevation of one of the contact disks in the mechanism shown in Figs. 5, 6 and 7.

Referring first to Fig. 1, herein the despatch tubes leading from stations A, B and C have respectively been designated 1^a, 1^b and 1^c. These tubes extend respectively to stations D, E and F, and the return tubes from these latter stations have been designated 2^a, 2^b and 2^c. The delivery terminals 3 at stations D, E and F are of a well known type; carriers emerging therefrom in the direction of the arrows through suitable clapper valves 4; the exemplified despatch 85 system being of the vacuum type.

When one of the valves hereinafter referred to is opened, air enters at the open end of the corresponding one of the tubes 1^a, 1^b, etc., and propels a carrier which may have been inserted in said open end upwardly to the corresponding terminal 3 and out through its valve 4; the current of air normally returning toward the lower station from the corresponding terminal 3 through 95 the tube 2^a, 2^b or 2^c, as the case may be; and being led off laterally from the line of travel of the carrier through a suitable conduit 5, and thence through an exhaust tube 6 past a valve 7 (above referred to) and into the 100 drum 8, or the like, from whence it flows through the blower 9 in the usual manner; this blower conveniently exhausting to the atmosphere at 10 and being driven by an electric motor 11. At substantially the entrance to each of the tubes 1^a, 1^b and 1^c, there is a contact box 12, the details of which are shown in Fig. 3. Herein a trip or lever 13 extends into the path of carriers being despatched, and is pivoted at 14 so that it may 110

be thrust upwardly and aside by each carrier as it is inserted into the transmission tube. A pair of resilient contact strips 15 and 16 are disposed adjacent the hub of this lever; strip 15 having a projection near its free end which is normally seated in a depression in the lever hub, but which when lever 13 is rotated counter-clockwise, as viewed in Fig. 3, by a passing carrier, is cammed out of said depression so that contact 15 is forced into engagement with the contact 16; thereby closing an electric circuit now to be described.

Current for this circuit may be conveniently supplied by a battery 17 or any other suitable and preferably low voltage source of current. When engagement is effected in the manner above described between contacts 15 and 16, current may flow from this battery through wire 18 to a wire 19^a, 19^b, or 19^c, according to which of the tubes leading from the several lower stations, is being used. This current passes from wire 19^a, for example, through contacts 15 and 16, at station A, and a wire 20^a to one of the circuit making and breaking devices, details of which have been shown in Figs. 5, 6, 7 and 8. For convenience this particular device has been broadly designated 21^a and wire 20^a leads thereinto through, for example, the base plate 22 thereof up to a magnet 23, which controls one of the contact disks hereinafter referred to; current passing through this magnet emerges therefrom through a wire 24 to a wire 25^a, and the latter extends to a lead 26 which runs back to the battery.

The energization of magnet 23 attracts its armature 27 which is mounted upon lever 28 pivoted at 29 in the upper extremity of a bracket 30. The free end of the lever 28 has a slotted connection 31 with an escapement like member 32 and the latter is pivoted upon a shaft 33 in a frame 34.

Below the shaft 33 in this frame is a second shaft 35 upon which are loosely mounted two wheels respectively designated 36 and 36'. Each of these wheels is toothed around the periphery thereof as at 37, in Figs. 5, 6 and 7; and the escapement 32, above referred to, engages the teeth 37 of wheel 36, while a similar escapement 32' is correspondingly adapted to actuate the wheel 36' through its engagement with the teeth 37 of said wheel. The escapements 32 and 32' may be spaced apart by a sleeve 38 and the wheels 36 are preferably provided with hubs which bear against each other and properly space these elements apart.

Attached, as by means of rivets, to the wheels 36 and 36' are disks of fiber or other suitable insulating material, respectively designated 39 and 39', and each of these insulating disks carries a cup-like contact member the bottom of which bears against

the inner side of these disks, while the flanges of said cup-like elements are disposed around the peripheries of the disks.

These cups have been respectively designated 40 and 40', and each preferably having a hole 41 in the center thereof through which the hub of the corresponding wheel 36-36' may project. The member 40 is cut away as at 42, so that, as shown in Figs. 5, 6 and 7, the flange thereof is substantially unimpaired, but a recess is provided in the lateral face thereof through which the insulating material of the disk 39 is exposed.

The member 40' instead of being cut away as is the cup 40, carries a spring contact 43 which may be riveted thereto at 44 and which is so shaped that its free end projects resiliently out toward the disk 39 and normally extends into the aperture 42 and contacts with the surface of this said disk exposed at this point.

Mounted upon the base 22 are two resilient contact strips designated 45 and 45', which respectively bear against the flanges of the conductive members 40-40'. Wires 46 and 47 extend from the strips 45-45' respectively to positive and negative leads 48 and 49; and since in Fig. 1 there are 3 valves 7, for convenience and as there are several sets of these wires 46-47, they have been respectively designated 46^a, 46^b, 47^a, 47^b, etc.

A solenoid 50^a is introduced into the line or wire 47^a while correspondingly a solenoid 50^b is connected in the wire 47^b, etc.; so that when contact is established between the strip 43 and the cup 40 of the device designated 21^a, current will flow through the positive lead 48 through wire 46^a, strip 45, cup 40, spring contact 43, cup 40', strip 45', wire 47^a and solenoid 50^a to the negative lead 49.

Whenever a carrier is inserted into the open end of the tube 1^a, this circuit is completed because of the energization of magnet 23 in the manner above described, the movement of whose armature causes the escapement-like member 32 to rotate clockwise as viewed in Fig. 5 so that the wheel 36 is advanced in the direction of the arrow indicated thereupon, one step, and no more than one step for any single actuation of the armature 27. The whole of this step is not effected solely by the descent of the armature, since the release of the armature upon the deenergization of magnet 23 permits of a counter-clockwise rotation of member 32 by a spring 51, and this movement of the element 32 completes the step.

The wheel 36 is, however, advanced sufficiently by the downward movement of armature 27 to effect an engagement between the contact strip 43 and the cup 40, so that immediately after a carrier has been thus inserted into the tube for despatch from station A, the valve 7 corresponding to such

station will be opened by its solenoid and air will flow upwardly through tube 1^a and downwardly through the tube 2^a and exhaust pipe 6 to the drum 8. The carrier 5 will be propelled by this flow of air toward station D, and just before it enters the terminal 3, said carrier will pass through a casing 52 which constitutes a portion of said tube 1^a.

- 10 Within this casing are preferably 3 contact actuating levers respectively designated 53, 54 and 55. Levers 53 and 54 have a relatively small movement and are adapted to be displaced laterally or counter-clockwise, 15 as viewed in Fig. 4, by the felt heads of a carrier. A carrier 56 has been shown in full lines in the tube 1^a, in Fig. 1, and comprises the usual body of brass tubing or the like into which messages or other articles 20 may be placed, and which body has at each extremity thereof a felt head which projects out beyond this body, or therearound, a short distance. When the front head of the carrier impinges against, for example, the lever 53; this lever is swung around and thereby cams into engagement contacts 57 and 58, in similar fashion to the manner in which contacts 15 and 16 are engaged by the action of the lever 13 above described. 25 As soon as this head of the carrier has passed the point of lever 53, the latter is snapped back into its normal position by its spring 59; there being sufficient clearance between the body of the carrier and the tube 30 to permit of this action.

Levers 53 and 54 have their carrier head engaging points spaced apart a distance substantially equal to the distance between the felt heads of the carrier plus the thickness 40 of one head, so that each carrier is adapted to operatively displace levers 53 and 54 simultaneously for just one instant as it passes said levers. The lever 55 is adapted for somewhat greater movement than levers 53 45 and 54 in that its point normally moves sufficiently far into the tube to insure its being displaced not only by the felt heads of the carrier but also by the body thereof. When a carrier impinges against lever 53 it there- 50 by cams into engagement contacts 60 and 61 which are controlled by this lever.

The lever 54 controls contacts 62 and 63 in similar fashion, and all three sets of these contacts are in series; a wire 64 connecting contact 57 with contact 60 and a wire 65 connecting contact 61 with contact 63. From contact 58 extends a wire 66 and a wire 67 similarly extends from contact 62.

By reason of the provision of these three 60 sets of contacts every carrier which passes through the casing 52 will invariably complete a circuit which includes the wires 66 and 67 just at the instant that this carrier occupies the position in which it is shown 65 in dotted lines in Fig. 4.

The reason that three sets of contacts are provided instead of one or two sets is this: If one set of contacts were used, controlled by lever 55, for example, then if two carriers were about to emerge from tube 1^a, the 70 second of these carriers being almost in contact or quite in engagement with the first, then lever 55 would be displaced to effect contact between members 60 and 61 but once for these two carriers, whereas it is highly 75 desirable in operating a system such as that herein described to have each carrier individually close the circuit through wire 66 once.

If, on the other hand, a single operating 80 lever such as that designated 53 were to be provided, then such lever would be actuated twice for every single carrier which passed it and the circuit through wire 66 would hence be completed twice for such a carrier, 85 owing to the successive engagements of the heads of this carrier with said lever. If some provision be made for spacing apart the adjoining heads of closely succeeding carriers, it is feasible to use a single contact 90 in a casing 52, but owing to the fact that most of the carriers in use to-day have flattened heads which are adapted to abut against each other closely, it is obvious that if two such closely succeeding carriers should 95 move past the contact lever 53, then the first head would energize wire 66 once, and the two adjoining heads of the two carriers would actuate lever 53 but once, thereby re-energizing wire 66 a second time, while the 100 rear head of the second carrier would again energize wire 66;—making three times in all; whereas to maintain proper actuation of the system when in use, a single lever such as that designated 53, would have to be actuated by said two carriers so as to energize 105 wire 66 four times.

Evidently if two levers, each of which are adapted to make a contact every time a carrier head passes each one of them, be disposed as shown in Fig. 4, then the wire 66 will be energized once and once only, for each carrier which passes through the casing 52, except in the one case when two carriers, one following the other, happen to be so 110 spaced apart in the casing while traveling therethrough that the rear head of the foremost carrier presses against lever 54, while the first head of the rear carrier presses against lever 53. It is for just this case that 115 the third contact 55 is provided, since at such time lever 53 would occupy its innermost position; there being no body of the carrier in contact therewith to hold it in its contact making position. Therefore if two 120 carriers should be so disposed, while they would complete the circuit at contacts 57 and 58, 62 and 63 the said circuit would still be broken between contacts 60 and 61.

From the foregoing it is evident that 130

three sets of contacts with actuating parts such as have been described, will unfailingly cause the energization of the circuit including wire 66, once and once only for each carrier which passes through the casing 52.

Referring again to Fig. 1, it will be observed that wire 66 is connected to a lead 68 which extends to a wire 18 which runs from 10 the battery, while the wire 67 connects contact 62 with a magnet 23', disposed alongside of the magnet 23, above referred to, and since there are a plurality of stations D, E and F, the wire 67 which leads from 15 station D has been designated 67^a and the corresponding wires for the other stations 67^b and 67^c.

The magnet 23' controls an actuating mechanism for the wheel 36' which is substantially identical with that already discussed in connection with wheel 36, so that it may suffice here to say that every time a magnet 23' is thus energized by the passage 25 of an emerging carrier through the casing 52 at a given station, the disk 40', which carries a contact spring 43 and which corresponds to such station, is advanced one step in the same direction that the corresponding disk 40 is advanced by the previously described mechanism.

It follows from this that every time a carrier is inserted at station A, for example, for despatch to station D, the disk 40 in the apparatus 21^a, will be cumulatively advanced 35 substantially one step; causing the solenoid 50^a to be energized and thus opening the preferably balanced valve 7, to establish a carrier propelling current of air to transmit said carrier to station D.

40 When this carrier is about ready to discharge at station D, its passage through the casing 52 at this station advances the disk 40' one step, so as to cause the spring 43 to tend to catch up with the opening or 45 recess 42 in the cup 40. If no other carrier has been inserted for despatch from station A to station D, before this first despatched carrier has been passed through casing 52, then the free end of strip 43 will again be 50 brought into coincidence with the recess 42; breaking the circuit through wire 47^a and permitting the core of solenoid 50' by its weight, or in any other suitable manner, to close the valve 7 and stop the further expenditure of power through this line. If, 55 however, a second carrier has been inserted into the tube 1^a before the first carrier thus emerges therefrom, such second carrier will have caused the disk 40 to be advanced 60 a second step, so that even when the first carrier thus causes the disk 40' to move around a single step, still contact 43 will be in engagement with cup 40 and valve 7 will be maintained open. Practically the 65 instant, however, that this second carrier

also emerges at station D, valve 7 will be closed. Thus there is no dependence upon any time interval; but a mere insertion of a carrier into the system starts the expenditure of power to transmit said carrier, and it will make no difference whether this carrier be followed by a second, third, fourth or fifth carrier in rapid succession and before the emergence of the first, in so far as the operation of the system is concerned. 70 Assuredly, the emergence of the last of these carriers from the lines will cause a shutting down of the power.

For transmitting carriers from station D to station A, for example, a second power control device 21^a is provided, and the downward passage of a carrier being despatched through the contact box 12 at station D will in corresponding fashion, through the instrumentality of the mechanism 21^a, effect 85 the opening of the valve 7 which corresponds to stations A and D.

Each of the devices 21^a and 21^b act independently of each other and obviously as long as a single carrier is in course of transit in either direction, between stations A and D, the said valve will be maintained open; while at almost the instant that the last carrier emerges from the tubes 1^a and 2^a, 90 considered collectively, said valve will close.

Referring now more particularly to the construction shown in Fig. 2, herein in place of controlling valves, or the like, whereby to control the expenditure of power, the motor itself is directly controlled by power control mechanisms 21, which may be identical with those used in the previous system. The air current in the present case, when the motor is in operation, flows through the tube 1 from the open end thereof at station G, in 100 the direction of the arrow indicated on this tube to station H and from thence back through the terminal 3 and tube 2 to the offset conduit 5, exhaust tube or pipe 6, drum 8 and blower 9 to the atmosphere at 10. 105 Contact boxes 12 may be provided adjacent stations G and H, so that the instant that a carrier is inserted for despatch at either of these points, one or the other of the corresponding control mechanisms 21^a or 21^b 110 will have the element 40 thereof advanced one step. Correspondingly the passage of a carrier through the casing 52 at either station G or station H will effect the single step displacement of the contact cup 40' in 115 the corresponding power control device, so that in so far as the operation of this system to this point is concerned it is substantially identical to that already discussed.

In the present case the circuit making and 120 breaking parts 40—40' are in circuit with the motor 11 so that the moment that contact is made between spring 43 and the cup 40 of either of the devices 21^a or 21^b, current will flow from the positive main 48, through 125

the motor and thence through lead 47 and one or the other of its branches 47^g or 47^h, to the contact 45', cup 40', spring 43, cup 40, strip 45 and wire 46^g or 46^h, as the case 5 may be, to the negative lead 49.

As long, therefore, as one or the other of the contacts 43 is operatively disposed with respect to its corresponding contact cup 40 the motor will continue in operation, and 10 by reason of the construction shown, almost immediately after the emergence of the last carrier through either of the tubes 1 or 2 said motor will be shut down, or the expenditure of power will be otherwise con- 15 served.

For the purpose of illustrating how a plurality of despatching points may be located along a transmission tube, I have somewhat diagrammatically indicated, below the station H, a despatching terminal J, provided with the usual valve 69 below which is disposed one of the contact boxes 12 with wires 19^j and 20^j respectively leading into wire 19^b and 20^b which extend to contacts at 25 the station H, so that the box 12 at station J is in parallel with box 12 at station H.

When therefore, a carrier is despatched at either station H or station J the contact cup 40 of the power control device 21^h will 30 be advanced one step, and this joint control from two points of this device will not throw out of step contact parts thereof, since carriers inserted at both H and J emerge at station G, where the element 40' of this same 35 device is controlled by the triple contacts in casing 52 of this latter station.

I have not attempted to apply designating characters to all of the wires, since owing to the similarity of the several circuits, the 40 course of current therethrough will at once be apparent in view of the above disclosure. Suffice it to say, however, that in general a scheme of nomenclature has been followed in which like numerals designate like wires 45 or parts, and where such numerals have a supplementary letter, the wires so designated correspond to a station having a like letter. In general each despatching point is provided with a contact making box 12 50 from which electrical connections extend to a power control circuit making and breaking device which corresponds to such station, so as to effect an energization of the magnet 23 of such device for each carrier despatched 55 from a station; while at each point from which a carrier may emerge from the system, or substantially adjacent said point, there is a contact box or casing 52 from whence electrical connections extend to the 60 magnet 23' of the power control device corresponding to the given line.

If a plurality of despatching points be located along a single transmission line, there may occur at comparatively rare times, a 65 simultaneous despatch of carriers from two

such despatching points, in which case the element 40 corresponding to both of said points would be advanced but a single step. It is therefore desirable where such an arrangement of the system is contemplated, to so 70 dispose each despatching terminal that the carrier may be dropped freely thereinto to make contact merely momentarily as it passes the trip or lever 13 below such despatching points, in order that the time during which the corresponding contacts 15 and 16 are held in engagement may be reduced to a minimum. This greatly reduces the chance of so causing this particular arrangement of the system to operate in an abnormal 75 manner. 80

Even, however, if the elements 40-40' of a given power control device should get out of step, the only harm which can result will be that the power will continue to be expended until it is observed by some one that the system is not operating properly, and in any case no carrier will be left in the system. 85

In certain of the appended claims I have referred to the elements 40-40' as "rotary" 90 parts, in contradistinction to reciprocatory or to and fro moving parts; since a very great advantage is obtained when said elements are mounted for step-by-step movement continuously ahead, as shown;—in that the neutral position of these parts with respect to each other becomes cyclic in character and there is hence no necessity for a retrograde step or movement of one or the other, or both, of said parts at a time. 95

Having thus described my invention what I claim is:— 100

1. In a carrier despatch system, a way having therewith a plurality of stations, means to propel carriers along said way, 105 step-by-step acting means, controlled from one of said stations from which carriers are despatched, for rendering said propelling means operative to propel a carrier from said station toward another one of the same, 110 said step-by-step acting means being advanced a step for each carrier despatched, means to thus control said step-by-step acting means, and co-acting means to limit the operation of said propelling means substantially as soon as said way is clear of all despatched carriers and normally only when said way is thus clear, said co-acting means having an actuating part along the path of carriers in course of transit near their point 115 of delivery and said part being separately actuated by each carrier as it passes the same irrespective of the proximity of such carrier to any carrier in advance thereof. 120

2. In a carrier despatch system, a way 125 having therewith a plurality of stations, means to propel carriers along said way, rotarily mounted step-by-step acting means, controlled from one of said stations from which carriers are despatched, for rendering 130

said propelling means operative to propel a carrier from said station toward another one of the same, said step-by-step acting means being advanced a step for each carrier despatched, means to thus control said step-by-step acting means, and co-acting means to limit the operation of said propelling means substantially as soon as said way is clear of all despatched carriers and normally only 10 when said way is thus clear, said co-acting means having an actuating part along the path of carriers in course of transit near their point of delivery and said part being separately actuated by each carrier as it 15 passes the same irrespective of the proximity of such carrier to any carrier in advance thereof.

3. In a carrier despatch system, a way having therealong a plurality of stations, 20 power means to propel carriers along said way, step-by-step acting means for rendering said power means operative to propel carriers, controlling means for a part of said step-by-step acting means, disposed ad-

25 jacent one of said stations, controlling means for another part of said step-by-step acting means, disposed at a point relatively remote from said first mentioned controlling means, one at least of said controlling means 30 being actuated by each carrier passing thereby, as said carrier approaches the point at which it ultimately comes to rest, said step-by-step acting means having rotary parts thereof adapted to normally occupy a neutral position with respect to each other and 35 one of said controlling means acting to change this normal relationship of said parts while the other of said controlling means acts to restore said relationship.

40 4. In a carrier despatch system, a way having therealong a plurality of stations, power means to propel carriers along said way, a plurality of elements which normally occupy a determined relationship with respect to each other, said elements co-acting 45 to control the expenditure of power by said power means, substantially independent controlling means for each of said elements, one of said controlling means normally acting, 50 each time it is rendered operative, to displace one of said elements one step for each carrier despatched and to thereby destroy said normal relationship, and another of said controlling means acting to counter- 55 act the action of said first mentioned one of said controlling means and to restore said relationship, the second of said controlling means being rendered operative with certainty each time that a carrier being delivered 60 passes a part of said last mentioned controlling means, said part having provisions to insure against improper actuation of said second controlling means resulting from closely following carriers.

65 5. In a carrier despatch system, a way

having therealong a plurality of stations, power means to propel carriers along said way, a plurality of elements which normally occupy a determined relationship with respect to each other, said elements co-acting 70 to control the expenditure of power by said power means, relatively widely spaced apart controlling means for each of said elements, one of said controlling means normally acting, each time it is rendered operative, to displace one of said elements one step for 75 each carrier despatched and to thereby destroy said normal relationship, and another of said controlling means acting to counteract the action of said first mentioned one of said controlling means and to restore said relationship, the second of said controlling means being rendered operative each time that a carrier being delivered passes a part 80 of said last mentioned controlling means, said part having provisions to insure against improper actuation of said second controlling means resulting from closely following carriers.

6. In a carrier despatch system, a way 90 having therealong a plurality of stations, power apparatus to propel carriers along said way, a plurality of independently movable rotatably mounted elements which normally occupy a determined relationship 95 with respect to each other, said elements co-acting to control the expenditure of power by said power apparatus, and controlling means for each of said elements, one of said means normally acting each time it is rendered operative, to displace one of said elements normally farther and farther from 100 said relationship, another of said means acting, each time it is rendered operative, to move a second of said elements so as to 105 tend to catch up with the first, whereby to ultimately reestablish said relationship, said first mentioned controlling means being normally actuated once for each carrier despatched and said second mentioned controlling means being normally actuated once as each of the so despatched carriers passes a determined point in said way.

7. In a carrier despatch system, a way having therealong a plurality of stations, power means to propel carriers along said way, mechanism to control the expenditure of power by said power means, means including a control device at one of said stations whereby as each carrier is despatched 115 from such station, a part of said mechanism will be correspondingly set to cause said power means to expend power to drive said carrier along said way, and auxiliary means including a contact device at a point in said 120 way, relatively adjacent another one of said stations and one at which said carrier is to be delivered, for electrically setting a part of said mechanism to counteract the effect of the action of said first device, each of the 125 130

respective actions of said devices upon said mechanism being cumulative and each single action of one of said devices normally offsetting a single action of the other of said devices.

5 8. In a carrier despatch system, a way having therewith a plurality of stations, power means to propel carriers along said way, mechanism to control the expenditure of power by said power means, means actuated by each successive carrier despatched from a station to cumulatively set a part of said mechanism to cause said power means to expend power to drive carriers along said 10 way, and means, including an electric circuit controlled by the so despatched carriers after they have traversed a part at least of said way, for cumulatively setting a part of said mechanism to counteract the cumulative 15 setting aforesaid, whereby to restore the parts of said mechanism to their neutral positions with respect to each other substantially as soon as said way is clear of all carriers.

20 9. In a carrier despatch system, a way having therewith a plurality of stations, power means to propel carriers along said way, mechanism to control the expenditure of power by said power means, said mechanism comprising two rotatable elements both 25 of which normally rotate in the same direction when actuated, means at one of said stations for controlling one of said elements, and means substantially at another of said 30 stations for controlling the other of said elements, each of said elements controlling means being adapted to cause the advance of the corresponding element one step for each actuation of such corresponding controlling means.

35 10. In a carrier despatch system, a plurality of contacts, a way having therewith a plurality of contact making parts each of which controls a set of said contacts, power means to propel carriers along said 40 way, mechanism to control said power means, and electrical connections between said contacts and said mechanism, for controlling said mechanism from said parts, the 45 said contact making parts which are actually engaged cumulatively by a single carrier at a determined point along said way being at least two in number and the contacts controlled by said parts being all in 50 series with each other.

55 11. In a carrier despatch system, a plurality of contacts, a way having therewith a plurality of contact making parts each of which controls a set of said contacts, power means to propel carriers along said way, mechanism to control said power means, and electrical connections between said contacts and said mechanism for controlling said mechanism from said parts, the said contacts making parts which are actually en-

gaged cumulatively by a single carrier at a determined point along said way being three in number and the contacts controlled by said parts being all in series with each other.

70 12. In a pneumatic despatch system, a plurality of contacts, a carrier, a transmission tube having at a determined point therein a plurality of contact making parts each of which parts controls a set of said contacts, a mechanism controlled by the passage of said carrier past said determined point, and electrical connections between said sets of contacts and said mechanism, said carrier having spaced apart enlarged portions adapted to simultaneously operatively engage said plurality of contact making parts only when said carrier is located at said determined point.

75 13. In a pneumatic despatch system, a plurality of contacts, a carrier, a transmission tube having at a determined point therein a plurality of contact making parts each of which parts controls a set of said contacts, a power control mechanism for 80 said system controlled by the passage of said carrier past said determined point, and electrical connections between said sets of contacts and said mechanism, said carrier having spaced apart enlarged portions 85 adapted to simultaneously operatively engage said plurality of contact making parts only when said carrier is located at said determined point.

90 14. In a device of the class described, in combination, a carrier having a head at each end thereof of greater diameter than the body of said carrier, a conduit through which said carrier travels and a plurality of co-acting contact making parts one of 95 which is adapted to be operatively disposed when in engagement with the body of said carrier and two others of which are adapted to be simultaneously operatively disposed by the heads of said carrier, a mechanism controlled by the passage of said carrier past a determined point in said conduit, and electrical connections between said parts and said mechanism.

100 15. In a device of the class described, in combination, a transmission tube, a plurality of carriers adapted to closely follow each other through said tube, said carriers having portions thereof of relatively different sizes, a plurality of contact parts disposed to be operatively engaged by different portions of each of said carriers as it passes said parts, and a mechanism electrically controlled by said parts only when a determined actuation of a determined plurality of said parts has been effected by a single passing carrier, said actuation of said plurality of parts by a plurality of said carriers being normally impossible.

105 16. In pneumatic despatch tube apparatus.

5   tus, a transmission conduit having there-
    along a plurality of stations, means to es-
    tablish a carrier propelling current of air
    through said conduit, means including a
    5   rotary step-by-step acting part, actuated
    substantially upon the despatch of a carrier,
    for rendering said first mentioned means
    operative to establish said current of air to
    propel a carrier from one of said stations
    10   toward another, said step-by-step acting
    part being advanced rotarily one step for
    each carrier despatched through said con-
    duit, and co-acting means to disestablish
    15   said carrier propelling current of air sub-
    stantially as soon as said conduit is clear
    of all despatched carriers and normally
    only when said conduit is thus clear.

17. In pneumatic despatch tube apparatus, a transmission conduit connecting a
20   plurality of stations, means to establish a
    carrier propelling current of air through
    said conduit of sufficient force and dura-
    tion to positively insure the proper trans-
    mission of a plurality of successive carriers
25   simultaneously *en route* through said con-
    duit, past a determined point therein, co-
    acting means to disestablish said carrier
    propelling current of air only when said
    conduit, at least up to said point, is free
30   from carriers in course of transit, said co-
    acting means being independent of time
    running from the despatch of said carriers
    and being further independent of the pres-
    sure of said air current, and means, also in-
35   dependent of said time and pressure, for
    actuating said co-acting means when said
    conduit is thus free of said carriers.

18. In pneumatic despatch tube apparatus, a transmission conduit having there-
40   along a plurality of stations, means to es-
    tablish a carrier propelling current of air
    through said conduit of sufficient force and
    duration to positively insure the proper
    transmission of a plurality of successive car-
45   riers simultaneously *en route* through said
    conduit, past a determined point therein,
    and electrically controlled co-acting means
    to thereafter disestablish said carrier pro-
    pelling current of air only when said con-
50   duct, at least up to said point, is free from
    carriers in course of transit, said co-acting
    means being free from time element instru-
    mentalities and being adapted to operate
    immediately upon the passage of the last
55   carrier in said conduit past said determined
    point, and contact making means, a part
    of which is located at said point, for elec-
    trically actuating said co-acting means
    when said conduit is thus free of said car-
60   riers.

19. In pneumatic despatch tube apparatus, a transmission conduit having there-
    along a plurality of stations, means, includ-
    ing a rotary step-by-step acting part, to
65   establish a carrier propelling current of

air through said conduit, co-acting means,
also including a rotary part, to thereafter
disestablish said carrier propelling current
of air only when said conduit is free from
carriers in course of transit and requiring
70   such air current to propel them, and means,
    controlled by carriers in course of delivery,
    for causing actuation of said last mentioned
    rotary part.

20. In pneumatic despatch tube apparatus,
75   a transmission conduit having there-
    along a plurality of stations, carrier con-
    trolled means to establish a carrier propel-
    ling current of air through said conduit,
    co-acting carrier controlled means, includ-
80   ing a rotary element, which directly co-acts
    with a part of the carrier controlled means
    first aforesaid, to disestablish said carrier
    propelling current of air only when said
    conduit is free from carriers in course of
85   transit and requiring such air current to
    propel them, said co-acting means being
    free from time element instrumentalities
    and being adapted to operate immediately
    upon the passage of the last carrier in said
90   conduit past a determined point in the nor-
    mal path of travel of said carrier, and
    means to actuate said co-acting means upon
    the passage of said last carrier past said
    point.

21. In a carrier despatch system, a way
95   having therealong a plurality of stations,
    power means to propel carriers along said
    way, mechanism to control the expenditure
    of power by said power means, means actu-
    ated by each successive carrier despatched
100   from a station to cumulatively set a part
    of said mechanism to cause said power
    means to expend power to drive carriers
    along said way, and means, including an
    electric circuit controlled by the so des-
105   patched carriers after they have traversed
    a part at least of said way, for cumulatively
    setting a part of said mechanism to counter-
    act the cumulative setting aforesaid, where-
    by to restore the parts of said mechanism
110   to their neutral positions with respect to
    each other substantially as soon as said way
    is clear of all carriers, said last mentioned
    means including contact-controlling provi-
    sions for said circuit to insure each passing
115   carrier's individual control of said circuit.

22. In pneumatic despatch tube apparatus, a transmission conduit having there-
120   along a plurality of stations, means to es-
    tablish a carrier propelling current of air
    through said conduit, step-by-step acting
    means, actuated substantially upon the des-
    patch of a carrier, for rendering said first
125   mentioned means operative to establish said
    current of air to propel a carrier from one
    of said stations toward another, said step-
    by-step acting means being advanced one
    step for each carrier despatched through
130   said conduit, and co-acting means to oper-

ate independently of said air current to dis-establish said carrier propelling current of air substantially as soon as said conduit is clear of all despatched carriers and normally only when said conduit is thus clear.

23. In pneumatic despatch tube apparatus, a transmission conduit having therealong a plurality of stations, means to establish a carrier propelling current of air through said conduit, means, including a rotary step-by-step acting part, actuated substantially upon the despatch of a carrier, for rendering said first mentioned means operative to establish said current of air to propel a carrier from one of said stations toward another, said step-by-step acting means being advanced one step for each carrier despatched through said conduit, and co-acting means, directly controlled by actual physical contact of a part of the same with passing carriers, to disestablish with certainty said carrier propelling current of air substantially as soon as said conduit is clear of all despatched carriers and normally only when said conduit is thus clear.

24. In pneumatic despatch tube apparatus, a transmission conduit having therealong a plurality of stations, means, including a rotary step-by-step acting part, to establish a carrier propelling current of air through said conduit, and co-acting means, controlled directly by carriers in course of delivery and by said carriers alone, to there-after disestablish said carrier propelling current of air when said conduit is free from carriers in course of transit, said co-acting means including a rotary step-by-step acting part to co-act with the part aforesaid.

25. In pneumatic despatch tube apparatus, a transmission conduit having there-

along a plurality of stations, means including a rotary step-by-step acting part to establish a carrier propelling current of air through said conduit, co-acting means to thereafter disestablish said carrier propelling current of air when said conduit is free from carriers in course of transit and actuating means for operating said co-acting means strictly in accordance with the passage of carriers past said actuating means irrespective of the propinquity of said carriers to each other.

26. In a carrier despatch system, a way having therealong a plurality of stations, power means to propel carriers along said way, mechanism to control the expenditure of power by said power means, means actuated by each successive carrier despatched from a station to cumulatively set a part of said mechanism to cause said power means to expend power to drive carriers along said way, and means, including an impulse transmitting system controlled by the so despatched carriers after they have traversed a part at least of said way, for cumulatively setting a part of said mechanism to counteract the cumulative setting aforesaid, whereby to restore the parts of said mechanism to their neutral positions with respect to each other as soon as said way is clear of all carriers requiring power from said power means to propel them, said last mentioned means including provisions to positively insure each passing carrier's individual control of said impulse transmitting system.

In testimony whereof I have affixed my signature, in the presence of two witnesses. 80
CHARLES P. HIDDEN.
